Morris Firestone

UNITED STATES PATENT OFFICE.

DORIS CLEVELAND HARRIS, OF MOUNT VERNON, NEW YORK.

DESIGN FOR A LADY'S TRAVELING ROBE.

60,341.

Specification for Design.

Patented Feb. 7, 1922.

Application filed October 6, 1921. Serial No. 505,942. Term of patent $3\frac{1}{2}$ years.

To all whom it may concern:

Be it known that DORIS CLEVELAND HARRIS, a citizen of the United States, and resident of the city of Mount Vernon, in the county of Westchester and State of New York, has invented a new, original, and ornamental Design for Ladies' Traveling Robes, of which the following is a specification, reference being had to the accompanying drawing, forming part thereof, in which—

Fig. 1 is a front view of the robe shown in use; and

Fig. 2 is a rear view thereof.

I claim:—

The ornamental design for a lady's traveling robe as shown.

DORIS CLEVELAND HARRIS.
